UNITED STATES PATENT OFFICE.

PHILETUS W. GATES, OF CHICAGO, ILLINOIS, ASSIGNOR TO THE GATES IRON WORKS, OF SAME PLACE.

DESIGN FOR AN ORE-CRUSHER FRAME.

SPECIFICATION forming part of Design No. 32,884, dated June 26, 1900.

Application filed May 28, 1900. Serial No. 18,327. Term of patent 14 years.

To all whom it may concern:

Be it known that I, PHILETUS WARREN GATES, a citizen of the United States, residing at Chicago, in the county of Cook and State of Illinois, have invented and produced a new and original Design for Ore-Crusher Frames, of which the following is a specification, reference being had to the accompanying drawing, forming a part hereof.

10 In the accompanying drawing the figure represents a perspective view of an ore-crusher frame, showing my design.

As shown in the drawing, the leading or material feature of my design consists of a

15 central hub portion A, provided with a series

of arms B, joined together at their lower portions by and with an annular ring C.

Having described my invention, what I claim as new, and desire to secure by Letters Patent, is—

20

The design for an ore-crusher frame, as herein shown and described.

In testimony whereof I have signed my name to this specification in the presence of two subscribing witnesses.

PHILETUS W. GATES.

Witnesses:

H. M. VANCE,
EDW. V. SHERLOCK.
